UNITED STATES PATENT OFFICE.

BENJAMIN Q. P. FOSS, OF SAN FRANCISCO, CALIFORNIA, ASSIGNOR TO THE FOSS INTERNATIONAL ORE REDUCTION COMPANY, OF SAN FRANCISCO, CALIFORNIA, A CORPORATION OF ARIZONA.

AMALGAMATOR.

1,270,399.

Specification of Letters Patent. Patented June 25, 1918.

Application filed June 27, 1914. Serial No. 847,591.

To all whom it may concern:

Be it known that I, BENJAMIN Q. P. Foss, a citizen of the United States, residing at San Francisco, in the county of San Francisco and State of California, have invented certain new and useful Improvements in Amalgamators, of which the following is a specification.

This invention relates to improvements in amalgamators, and has for its object to provide an improved form of amalgamator adapted to thoroughly mix the metalliferous pulp or the like with the quicksilver or amalgamating material.

Another object is to provide an amalgamator comprising a casing and a rotary stirring member mounted for detachment to enable easy cleaning up of the mixing member and draining of the amalgamator.

Another object is to provide, in an amalgamator of the class described, means to prevent leakage of pulp or fluid past the ends of the mixing member.

Still another object is to provide, in combination with an amalgamator, improved bearing construction for detachably supporting the mixer in rotatable position, together with means for rotatably supporting the same in position for "cleaning-up".

Other objects will be set forth and made apparent in the following specification and accompanying drawings, in which:

Figure 1 is a horizontal section along line 1-1 of Fig. 3, showing the mixing member partially broken away;

Fig. 2 is a vertical longitudinal section of the same;

Fig. 3 is an end elevation;

Fig. 4 is a vertical transverse section;

Fig. 5 is a detail section showing the construction and arrangement of the metal plates and the webs;

Fig. 6 is a detail showing an end elevation of the structure shown in Fig. 5.

Like numerals refer to like elements throughout the drawings, in which:

10 designates generally the casing of my amalgamator comprising a semi-cylindrical bottom portion 11 provided with the supporting shoulders or flanges 11^a and outwardly extending bolting flanges 11^b. This bottom portion is provided with the drain trough 11^c inclined from one end to the other, as clearly shown in Fig. 2 and pro-

vided with the outward opening 11^d normally closed by the plug 11^e or the like. This trough 11^c is located at the bottom of the casing portion 11 which is adapted to drain the contents therefrom when so desired. Extending upwardly from and secured to the bottom portion 11, is the rectangular portion of the casing, indicated by numeral 12 and comprising ends 12^a and sides 12^b, as clearly shown in the drawings. An inlet trough or hopper 13 is provided at one side of the casing portion 12 discharging into the interior thereof and an outlet trough or spout 14 is provided at the opposite side thereof, the same being preferably arranged at the lower level than the inlet 13, as shown in Fig. 4. The ends 12^a and sides 12^b are secured together by bolts 12^c or the like and the entire portion 12 is secured by angles 12^d coacting with the sides 12^b to the flanges 11^b of the lower portion 11. The ends 12^a are provided with the side flanges 12^e, top flange 12^f and bottom flange 12^g, the latter being bolted to the corresponding of flanges 11^b of the bottom portion 11, by bolts 12^h or the like. A semicircular shoulder 12ⁱ is provided in each of the end member 12^a and the same is grooved as indicated by numeral 12^j, see Fig. 1, for the purpose to be hereinafter described. The top flanges 12^f are provided with the enlarged portions constituting lugs 12^k, centrally apertured. These end members 12^a are further provided with the circular raised portions 12^m, centrally apertured, as indicated by numeral 12ⁿ, see Fig. 2. Bearing sleeves 15 are located at each end of the machine and are formed with enlarged collars 15^a adapted to contact with the outer ends of the raised portions 12^m. The collars 15^a are further provided with the inwardly projecting circular flanges 15^b adapted to closely fit the aperture 12ⁿ. The sleeves 15 are provided with the Babbitt lining 15^c and have the enlarged recess or aperture 15^d near one end thereof, the collar 15^a being inwardly projected and forming one side of said recess, as clearly shown in Fig. 2. A threaded aperture 15^e leads outwardly from the recess 15^d, in which may be threaded a pipe for draining thereof or for injecting lubricant thereinto, if so desired. Spindles 16 are provided having their shanks 16^a journaled in the bearing sleeves

15. At the end of the shanks 16^a are inset wearing blocks 16^b slightly hollowed out or depressed, as indicated by 16^c. At their other ends spindles 16 are provided with the 5 enlarged plates 16^d and outwardly of these collars are located the tapered centering lugs 16^e. The end plates 12^a are each provided with the centrally apertured and threaded studs 12^b, in which are threaded 10 the posts 18. A cross-bar 19 extends between and is mounted on these posts 18, being secured in place adjacent the outer ends thereof by the respective pairs of nuts 18^a threaded on the posts 18. These cross-bars 15 19 are provided with the centrally enlarged and apertured hub portions 19^a through each of which is threaded the bolt or stock 20 having the head 20^a adapted to be engaged by a wrench or the like. This stock 20 is 20 provided with the tapered end adapted to fit in the depression 16^c of the wearing block 16^b, as shown in Fig. 2. A lock-nut 21 is threaded on the stock 20 on each side of the hub portion 19^a and these nuts 21 serve to 25 lock the stock in adjusted position, as will be apparent.

Located in the casing 10 is the mixing member 25 comprising the central shaft or tube 25^a having the end pieces 25^b formed therewith or secured thereto, as shown in 30 Fig. 2. These end pieces 25^b are centrally recessed as indicated by 25^c, the centrally located recesses 25^e forming seats for the centering lugs 16^e of spindle 16. The pieces 35 25^b are further provided with transverse grooves 25^d which are adapted to receive the plates 16^d of the spindle 16 and form a non-rotative engagement therewith. At each 40 end of the central shaft 25^a is secured a supporting disk or web 26 having outwardly extending ribs 26^a and a peripheral circular flange 26^b. The mixer is formed as a drum or shell by applying segmentary plates 27 of copper or the like. These plates 45 are secured at their sides by screws or studs 27^a to the flanges 28^a of a T-bar 28 which extends between and is secured to the spiders 26. Similarly the ends of the plates 27 are secured by bolts 29 or the like to the 50 flanges 26^b on the webs or frames 26, see Fig. 5. A plurality of outwardly extending blades or lugs 30 are provided, these blades 30 being provided with the portions 30^a inset into and riveted to the plates 27, as 55 shown in Fig. 5. These blades 30 are arranged in staggered rows, as shown for example in Fig. 1.

To support the portion of the shell between the end frames 26, I provide a circular strip 32, to which are secured the ends of spokes 33, which in turn are secured at their other ends by bolts 34 or the like to a hub or collar 35, which in turn is secured to the central shaft or tube 25^a by set screws 36. For rotating the mechanism 25 I pro-

vide driving mechanism comprising the main pulley 40 adapted to be driven from a belt or the like and secured to a shaft 41. This shaft is journaled at one end in the bearing 42 carried by the end plate 12^a and 70 is supported on its other side by bearing 43 carried by the pedestal 44 projecting upwardly from the adjacent bearing collar 15, as clearly shown in Fig. 2. Outwardly of the bearing 43 the shaft 41 carries the driving pinion 46 in mesh with the gear 47, which in turn is secured to the corresponding 75 spindle 16.

It will be apparent that rotation of the driving pulley 40 will operate to rotate the 80 gear 47 and when the spindles 16 are in position shown in Fig. 2 this rotation will be imparted to the mixer 25. The pulp, comprising ordinarily crushed ore and water or other fluid flows into the casing 85 10 through the inlet 13 in the direction of the arrow, see Fig. 4, and the mixer 25 is preferably rotated in the direction indicated by the corresponding arrow. The casing portion 11 preferably contains quicksilver 90 or the like and the blades or lugs 30 will operate to carry this pulp downwardly through the mercury and thoroughly commingle the two to produce the amalgam. The water and other fluid will flow upwardly over the top of the mixing drum 25 and out through the discharge spout 14, also serving to wash downwardly off the blades 30, any pulp which has emerged 95 from the quicksilver with the rotating 100 mixer 25. To prevent the passage of the pulp from the inlet 13 to the outlet 14 without contacting with the blades 30, that is, by passing between the ends of the mixer 25 and the end plates 12^a of the casing, I 105 provide circular packing strips 50 of suitable packing material and tightly compressed in the groove 51 formed in the semi-circular shoulder 12^b as shown in Fig. 2. At the rear side of this packing strip 50 110 is located a follower strip 52 and a plurality of adjusting screws 53 are threaded through the shoulder 12^b and abut against the side of the strip 52. The groove 51 is so located that the packing strip 50, when 115 the screws 53 are properly adjusted will press tightly against the flange 26^b of the webs 26, and a tight contact therebetween may be insured by means of the screws 53, thereby preventing flow of pulp or water 120 between the ends of the mixer 25 and the casing. When it is desired to "clean-up" the amalgamator, the plug 11^c may be removed and the amalgam allowed to flow out. At the same time an amount of the 125 amalgam will be clinging to the blades or lugs 30 and it is necessary to clean the same. To permit access for such cleaning with ease and rapidity, I provide rollers 60 mounted upon the spindles 61, these rollers 130

60 being provided with the reduced collar portions 60^a, as shown in Fig. 2. Spindles 61 are provided with the heads 61^a and are further provided with the shoulder 61^b intermediate their extremities and have their outer extremities threaded for engagement by nuts 62. When it is desired to "clean-up" eye-bolts may be inserted in the threaded apertures 26^c in the flanges 26^b of the web 26 and the mixer 25 may be raised bodily therefrom, the stocks 20 having first been withdrawn to permit withdrawal of the spindles 16, so that the mixer 25 is free to be raised or lowered from the casing. After such raising, the spindles 61 are inserted through the apertures 63 in the end plates 12^a and the nuts 62 tightened thereon. When in this position the mixing drum 25 will rest on the rollers 60, as will be apparent from examination of Fig. 2, so that the mixer 25 may be rotated around and the blades 30 thereof readily cleaned.

It is believed that the operation of my device is sufficiently clear from the above, and that further description is not necessary to enable those skilled in the art to understand the same.

It will be apparent that my machine is susceptible of improvements and modifications, and I do not wish to be restricted to the form shown and described beyond the scope of the appended claims.

I claim—

1. In a device of the class described, a casing, a mixing member rotatably mounted in said casing, said casing being provided with a semi-cylindrical portion, the inner surface thereof closely fitting a portion of said mixing member and adapted to hold amalgamating material to partially submerge said mixing member, and means to insure contact between the ends of said mixing member and said casing above the level of said material.

2. In a device of the class described, a casing, a mixing member rotatably mounted therein, means to insure a substantially fluid-tight contact between a portion of said casing and the ends of said mixing member, said means comprising a packing strip.

3. In a device of the class described, a casing, a mixing member rotatably mounted therein, means to insure a substantial fluid-tight contact between a portion of said casing and the ends of said mixing member, said means comprising a packing strip, and means to maintain said packing strip in contact with said mixing member.

4. In a device of the class described, a casing, a mixing member rotatably mounted therein, means to insure a substantial fluid-tight contact between a portion of said casing and the ends of said mixing member, said means comprising a packing strip, means to maintain said packing strip in

contact with said mixing member, said means comprising a follower strip, and screw threaded adjusting members coacting therewith.

5. In a device of the class described, a casing adapted to hold amalgamating material therein, a mixing member rotatably mounted in said casing and adapted to be partially submerged in said material, means to insure substantially fluid-tight contact between said casing and said mixing member above said material, said means comprising packing strips carried by said casing and contacting with the ends of said mixing member.

6. In a device of the class described, a casing adapted to contain amalgamating fluid, a mixing member rotatably mounted in said casing and adapted to be partially submerged in said fluid, said mixing member comprising a shell mounted on end webs, said webs having peripheral flanged portions, packing strips carried by said casing, said peripheral flanges of said webs being adapted to contact with said packing strips above said fluid.

7. In a device of the class described, a casing adapted to contain amalgamating fluid, a mixing member rotatably mounted in said casing and adapted to be partially submerged in said fluid, and adjustable means for effecting a fluid-tight contact between the ends of said mixing member and the adjacent parts of said casing.

8. In a device of the class described, a casing, spindles journaled in said casing and projecting thereinto, a rotatable mixing member adapted to be rotatably supported by said spindles in said casing, said spindles being arranged to permit disengagement therewith from said mixing member to permit removal of the latter from said casing, and means to maintain said spindles in engagement with said mixing member, said means comprising stock members coacting with and pressing against the ends of said spindles.

9. In a device of the class described, a casing, spindles journaled in said casing and projecting thereinto, a rotatable mixing member adapted to be rotatably supported by said spindles in said casing, said spindles being arranged to permit disengagement therewith from said mixing member to permit removal of the latter from said casing, and means to maintain said spindles in engagement with said mixing member, said means comprising stock members coacting with and pressing against the ends of said spindles, said stocks being adjustably mounted in cross-bars supported by said casing.

10. In a device of the class described, a casing, a mixing member rotatably mounted in said casing and adapted to be removed therefrom, and means to support said mix-

ing member when removed to non-mixing position above said casing, said means comprising rollers carried by said casing.

11. In a device of the class described, a casing, a mixing member rotatably mounted in said casing and adapted to be removed therefrom, and means to support said mixing member when removed to non-mixing position, said means comprising rollers detachably mounted in said casing and adapt-

ed to rotatably support said mixing member, said rollers being adapted to prevent the removal of said mixing member when the latter is in the casing.

In testimony whereof, I have subscribed 15 my name.

BENJAMIN Q. P. FOSS.
